(57) **CLAIM**

The ornamental design for an automobile, as shown and described.

DESCRIPTION

1. Automobile

Fig. 1.1 is a front and left side perspective view of an automobile showing our new design;

Fig. 1.2 is a rear and left side perspective view thereof;

Fig. 1.3 is a left side elevational view thereof;

Fig. 1.4 is a right side elevational view thereof;

Fig. 1.5 is a front elevational view thereof;

Fig. 1.6 is a rear elevational view thereof; and,

Fig. 1.7 is a top plan view thereof.

The bottom view of the automobile according to the present design is omitted since the bottom of the automobile is invisible in use.
